(57) **CLAIM**

The ornamental design for a clothes hanger, as shown and described.

DESCRIPTION

FIG. 1 is a perspective view of a clothes hanger with a support pole and a mounting structure for attaching the hanger to a column such as a support column of a head rest, the figure showing one side of the hanger,

FIG. 2 is a perspective view of the clothes hanger showing the hanger from the opposite side thereof; and,

FIG. 3 is a perspective view of the clothes hanger showing the hanger from the bottom rear of FIG. 1.

The hanger is intended to be mounted to a support column of a cars headrest for supporting cloth either behind a backrest or in front of the backrest.

1 Claim, 3 Drawing Sheets

FIG. 1

FIG. 2

FIG. 3
